DOOR LOCKING AND OPERATING DEVICE

Wesley W. Eager, Los Angeles, and Columbus A. Tierney, San Marino, Calif.

Application September 13, 1932, Serial No. 632,942

3 Claims. (Cl. 70—130)

This invention relates to closure operating and locking devices, and has for an object the provision of an improved and simplified device of this general classification which is particularly well adapted for, though not necessarily limited to, use in connection with the closure forming the subject matter of our co-pending application, Serial No. 620,884, filed July 5, 1932, of which this application is a continuation in part.

10 A more detailed object is the provision of an operating and locking device for a closure which requires for its operation rotary motion of a shaft or analogous member, the operating and locking device comprising a lever carried by said shaft and normally freely rotatable thereupon so as to make it impossible for unauthorized persons to turn the shaft, but provided with a suitable locking device whereby the lever may be engaged with the shaft so that the lever provides a convenient handle which may be turned manually to impart the necessary rotary motion to the shaft.

15 Another object is to provide a closure operating device which includes means for positively restraining the closure from moving away from either of its two extremes of movement without first moving the shaft upon which the operating lever is carried.

20 It is a further object of our invention to provide a device of the general character described, which is composed of a minimum number of parts, which is simple in design and which is inexpensive to manufacture and assemble, positive in operation, easy to adjust and easy and inexpensive to repair.

25 The invention possesses other objects and valuable features, some of which, with the foregoing, will be set forth in the following description of the preferred form of our invention. It is 30 to be understood that we do not limit ourselves to the specific disclosure made by the said description, as we may adopt variations of the preferred form within the scope of our invention, as set forth in the claims.

35 Referring to the drawing:

Figure 1 is a vertical sectional view taken transversely through a door having the operating and locking mechanism of the present invention operatively associated therewith. Portions of the figure are broken away to reduce its size.

40 Figure 2 is an enlarged view in side elevation of the operating and locking device.

45 Figure 3 is a more highly enlarged view in transverse vertical section taken upon the line 3—3 of Figure 2, with the direction of view as

indicated by the arrows. A portion of the figure is broken away to reduce its size.

Figure 4 is a longitudinal, vertical sectional view taken upon the line 4—4 of Figure 3, with the direction of view as indicated by the arrows. A portion of this figure also is broken away to reduce its size.

Figure 5 is an enlarged transverse, vertical sectional view, taken upon the line 5—5 of Figure 2, with the direction of view as indicated by the arrows.

In terms of broad inclusion, the closure operating device of the present invention comprises a shaft or analogous member rotatably mounted in a suitable support and operably coupled to the associated closure so that the closure may be opened and closed by rotary motion of the shaft. The only portion of the device which is accessible to unauthorized persons is a lever or handle which is mounted for free rotation upon an end of the shaft; and means operable by properly authorized persons is provided for rigidly connecting the lever to the shaft so that the shaft may be turned by means of the lever. This connecting means comprises a suitable lock, which may be left in such position that the lever and shaft are positively interconnected, but which may be manipulated so as to instantly disconnect the lever from the shaft, so that it is freely rotatable thereupon, the effect being positively to lock the closure in either fully opened or fully closed position, as the case might be, inasmuch as the handle itself is the only portion of the device which is accessible to unauthorized persons and consequently the rotary motion of the shaft which is necessary for movement of the door cannot be effected. Means are also provided for so retaining the shaft in either of its two extremes of movement that in order to move the closure or door the shaft itself must first be turned, thereby preventing inadvertent movement of the door from fully opened or fully closed position.

More specifically described, our improved closure operating and locking device is illustrated upon Figure 1 as being operably associated with a door 6 of the type forming the subject matter of our aforementioned application Serial No. 620,884, which is mounted by means of a suitable bracket structure 7 for pivotal movement to and from closed position, about an axis 8 spaced a material distance inwards from the inner face of the door 6. Figure 1 illustrates the door in its closed position, and it is adapted to be opened by swinging in a clockwise direction as viewed

upon that figure until it is disposed substantially horizontally and in an overhead position, leaving the doorway unobstructed for passage therethrough.

5 Our improved locking and operating device is indicated in its entirety at 11 and comprises a shaft 12 rotatably mounted in and extending through the wall 13 which defines the opening 14 with which the door 6 is associated. Preferably 10 the shaft 12 is enclosed within a suitable housing, such as a piece of tubing 16, the outer end of which is threaded into a collar 17 affixed to the outer face of the wall 13. Extra rigidity is imparted to the housing 16 by means of a brace 15 18 on one end of which a collar 19 is formed and on the other end of which a flange 21 is provided. The collar 19 encircles the housing 16, which is rigidly secured thereto as by a set screw 22; and the flange 21 is rigidly secured to the 20 inner face of the wall 13 as by a lag screw 23.

To the inner end of the shaft 12 a crank 26 is securely fastened as by a set screw 27. To the outer end of the crank 26 one end of a link 28 is pivoted and the other end 29 of the link 28 is pivoted to the bracket 7, the parts being so proportioned and arranged that when the crank 26 swings upwards from the position illustrated upon Figure 1 to the position illustrated upon Figure 2, the door 6 will be swung from 30 closed position to fully opened position. Whereas movement of the crank 26 through substantially 180° is all that is necessary to swing the door 6 through its entire range of movement, the crank 26 is capable of moving slightly beyond 35 both of its dead center positions, whereupon a lug 31, rigid with the crank 26, will come into engagement with abutments 32 or 33 as the case might be, carried by a collar 34, rigid with the inner end of the tubular housing 16. This serves 40 to retain the door 6 in either its fully opened or its fully closed position until the shaft 12 and the crank 26 carried thereby are moved, thereby preventing inadvertent movement of the door by forces applied to the door itself. In other 45 words, it is necessary for the operating device to receive the necessary actuation before the door can be moved.

The operating means whereby the rotary motion of the shaft 12 necessary to move the door 6 may conveniently be effected by properly authorized persons through the expedient of a handle or lever 41 carried by the shaft 12. This lever 41 is mounted upon that end 42 of the shaft 12 which projects through the wall 13; and 50 inasmuch as the protruding end 42 of the shaft 12 is completely enclosed within the head 43 which is formed at one end of the lever 41, the only portion of the operating device 11 which is accessible on the outside of the wall 13, is the lever 41 itself. Therefore, by so mounting the lever 41 upon the shaft 12 that the lever is 55 freely rotatable upon the shaft but adapted to be rigidly connected thereto by means operable by authorized persons only, we have provided an effective lock for the door 6, which makes it impossible for any but authorized persons to open the door.

A flange 46 is shown as being rigidly secured to the shaft 12 as by a pin 48 extending through the flange 46 and the end of the shaft 12, although it should be understood that any other suitable means for securing the flange 46 in position upon the shaft 12 may be employed. In order to permit assembly of the device, the head 43 is composed of two portions 49 and 51, secured together

as by a plurality of cap screws 52. In the portion 49 a recess 53 is formed for the reception of the flange 46 and the adjacent portion of the shaft 12; and the shaft 12 extends through a suitable opening 54 in the portion 51 of the head 43 into the recess 53, the above described parts being so proportioned and arranged that the lever 41 is freely rotatable with respect to the shaft 12.

10 The means for releasably locking the lever 41 to the shaft 12 includes a notch 56 formed in the periphery of the flange 46 and a pin 57 slidably mounted in the head 43 for movement axially of the pin 57 and parallel to the axis of the shaft 12 in such position that it may optionally be seated 15 within the notch 56 or withdrawn therefrom. For this purpose, a portion 58 of reduced diameter is formed on the pin which may be brought into registry with the flange 46 as illustrated upon Figure 4, under which circumstances the lever 41 20 will be freely rotatable upon the shaft 12. The pin 57 is slidably disposed within aligned holes 53 and 61 in the portions 49 and 51 respectively of the head 43, and is continually urged as by a spring 62 so as to move the reduced portion 58 25 out of registry with the flange 46 and to bring a portion 63 of greater diameter into registry therewith so that it seats within the notch 56. The pin 57 is of such length that when the larger portion 63 is disposed within the notch the forward 30 end 64 of the pin protrudes beyond the forward face of the head 43, thereby providing a conveniently manually operable portion which may be pressed into the head 43 against the action of the spring 62.

35 Within another recess 66 in the head 43 a detent 67 is pivotally mounted as by a pivot pin 68 rigid with the portion 51 of the head 43 and extending loosely through a laterally projecting arm 69 of the detent 67. The lower portion 71 of the 40 detent 67 is enlarged to provide sufficient stock to accommodate an aperture 72, into which projects a pin 73, rigid with and eccentrically disposed upon the rotatable cylinder 74 of a lock 76. Whereas any suitable type of lock 76 may be employed, that which has been selected for illustration comprises a barrel 77, rigidly anchored in the head 43 as by a set-screw 78, and the cylinder 74, which may be rotated within the barrel 77 45 only by means of the appropriate key. The parts are so proportioned and arranged that when the cylinder 74 is turned from the position in which it is illustrated upon Figures 3 and 4, the pin 73 will be carried downwards, swinging the detent 67 in a counter-clockwise direction as viewed 50 upon Figure 3, so as to withdraw the upper end 81 of the detent 67 from the hole 59 within which the pin 57 is slidable. This motion of the detent 67 is resisted by a leaf spring 82 under compression between the lower edge of the detent 67 55 and the bottom of the recess 66; but of course the detent 67 cannot be swung upwards to move the end 81 into the hole 59 except when the reduced portion 58 of the pin 57 is in registry with the flange 46, as will be understood clearly from 60 Figure 4. However, owing to the fact that the aperture 72 affords ample clearance for the pin 73, the cylinder 74 of the lock 76 may be returned to the position illustrated upon Figures 3 and 4, to permit removal of the key, without pressing the 70 pin 57 back into the head 43, under which circumstances the upper end 81 of the detent 67, will be pressed against the larger portion 63 of the pin 57. Consequently, when the pin 57 is pressed back into the head 43, the detent 67 will be forced 75

upward by the spring 82 so that it will retain the pin 57 in the position illustrated upon Figure 4 by engagement with the shoulder or abutment 86, which separates the portions 58 and 63 of the pin 57. The parts will be retained in this position until the proper key is inserted again into the lock 76 to effect rotation of the cylinder 74 and consequent withdrawal of the detent 67.

It is believed that the operation of the operating and locking device will readily be understood from the above description of its component parts. When the pin 57 is depressed so that it occupies the position in which it is illustrated upon Figure 4, the lever 41 will be free to rotate upon the shaft 12, so that unauthorized persons will be unable to effect movement of the door 6. However, by insertion of the proper key into the lock 76, the cylinder 74 may be turned, whereupon the lock pin 73 will withdraw the detent 67 from engagement with the abutment 86, permitting the spring 62 to force the pin 57 outwards, provided the lever 41 is in such position with respect to the shaft 12 that the notch 56 is disposed in registry with the pin 57. Preferably, the parts are so arranged that the notch 56 is in the under side of the flange 46 when the door 6 is closed, and the pin 57 is disposed directly under the axis about which the lever 41 is adapted to swing, when the lever hangs straight downwards, thereby causing the pin 57 automatically to come into registry with the notch 56 when the door 6 is closed and the handle 41 is permitted to hang freely. This affords convenience in the use of the device inasmuch as it permits the operator to unlock the door by the simple expedient of inserting the key and turning the cylinder 74 of the lock without having to devote any attention to the position occupied by the lever 41, which is swung by gravity into that position which brings the pin 57 into registry with the notch 56, thereby enabling the larger portion 63 of the pin 57 to move into the notch 56 and lock the lever 41 to the shaft 12 when the detent 67 is withdrawn. Locking of the door may be effected simply by pressing the portion 64 of the pin 57 into the head 43, thereby removing the portion 63 from the notch 56, which will permit the lever 41 to turn freely without effecting rotation of the shaft 12. When this occurs, the detent 67 will be pressed upwards by the spring 82, thereby retaining the pin 57 withdrawn from engagement with the flange 46 until the lock 76 again is actuated.

We claim:

1. In a device of the character described, a member to be turned, a flange rigid with said member and having a notch in the periphery thereof, operating means freely revoluble on said member and having a hole therein the axis of which is substantially parallel to the axis of rotation of said operating means, said flange extending into one side of said hole, and a pin 5
slidable within said hole optionally into or out of said notch said pin being supported within 10
said hole upon both sides of said flange.

2. In a device of the character described, a shaft, a flange rigid with said shaft and having a notch in the periphery thereof, operating means freely revoluble on said shaft and having a hole 15
therein the axis of which is substantially parallel to the axis of rotation of said operating means, said flange extending into one side of said hole, and said notch being complementary to said hole whereby the bore of said hole can be made continuous past said flange by bringing said notch 20
into registry with said hole, a pin 25
slidable within said hole and removably receivable within said notch to lock said operating means to said shaft, said pin being supported within said hole upon 30
both sides of said flange and substantially filling said notch and the associated portion of said hole when in locking position, and means releasably retaining said pin withdrawn from said notch.

3. In a device of the character described, a shaft, a flange rigid with said shaft and having a notch in the periphery thereof, operating means freely revoluble on said shaft and having a hole 35
therein the axis of which is substantially parallel to the axis of rotation of said operating means, said flange extending into one side of said hole, and said notch being complementary to said hole whereby the bore of said hole can be made continuous past said flange by bringing said notch 40
into registry with said hole, a pin 45
slidable within said hole and removably receivable within said notch to lock said operating means to said shaft, said pin being supported within said hole upon 50
both sides of said flange and substantially filling said notch and the associated portion of said hole when in locking position, spring means urging said pin into locking position, means holding said spring means inoperative, and a lock coupled to said holding means and adapted to withdraw said holding means from its operating position.
